UNITED STATES PATENT OFFICE

2,419,511

CABLE STRIPPER

Charles S. Vaughan, Jr., Tuscumbia, Ala.

Application January 5, 1945, Serial No. 571,443

1 Claim. (Cl. 81—9.5)

1

This invention relates to a cable stripper, and more particularly to a cable stripper adapted for the removal of the lead, and/or the lead and armor from cables.

A primary object of this invention is the provision of an improved cable stripper adapted for the ready removal of lead, or the like, from sheathed cables when desired.

An additional object of the invention is the provision of such a device which may be readily applied to and removed from cables for use.

Still another object of the invention is the provision of such a device with a cutting element adapted to be turned to a variety of angles, whereby the cable may be stripped by means of a single longitudinal cut, or a helical cut as may be desired.

A still further object of the invention is the provision of such a device provided with a removable insert, whereby a plurality of sizes of cables may be accommodated in a single device.

Still another object of the invention is the provision of such a device provided with an improved holder particularly adapted for use with large size cables.

Still another object resides in the provision of such a device which will be sturdy and durable in construction, reliable and efficient in use and operation, and relatively simple and inexpensive to manufacture.

Other objects reside in the combinations of elements, arrangements of parts, and features of construction, all as will be more fully pointed out hereinafter and shown in the accompanying drawings, wherein there is disclosed a preferred embodiment of this invention.

In the drawings:

Figure 1 is a front elevational view of one form of device embodying the instant inventive concept.

Figure 2 is an enlarged sectional view taken substantially along the line 2—2 of Figure 1, as viewed in the direction indicated by the arrows.

Figure 3 is an enlarged sectional view taken substantially along the line 3—3 of Figure 2.

Figure 4 is a sectional view taken substantially along the line 4—4 of Figure 3.

Figure 5 is a top plan view of the device.

Figure 6 is a sectional view taken substantially along the line 6—6 of Figure 1.

Figure 7 is a sectional view taken substantially along the line 7—7 of Figure 1, and

Figure 8 is a view similar to Figure 2, but showing a modified form of insert.

2

Similar reference characters refer to similar parts throughout the several views of the drawings.

Having reference now to the drawings, the device is comprised of a lower member generally indicated at 10, and an upper member generally indicated at 11.

The lower member 10 is comprised of a central block portion 12 having a longitudinally extending semi-cylindrical recess 13 therein. Extending outwardly from the central member 12 are two arms 14 and 15, semi-cylindrical in cross section. The extremity of the member 14 terminates in two upwardly extending, oppositely disposed lugs 16 provided with apertures, the extremity of the member 14 being bifurcated to provide a slot. The upper member 11 is comprised of a central body portion 17, and two transversely extending arms 18 and 19, each of 20 semi-cylindrical cross section, having a flat under surface adapted to engage the flat upper surfaces of the portions 14 and 15. The extremity of the member 18 terminates in a milled portion 20 adapted to fit between the lugs 16, aligned apertures being provided through the members 16 and the member 20 to accommodate a hinge pin 21 (see Fig. 7). The pin 21 is comprised of a shank section 22 having a slot 22' therein to permit the insertion of a screw driver, and a 25 threaded portion 23 engaging a threaded aperture in one of the members 16. The opposite ends of the members 15 and 19 are rounded, as at 24 and 25, respectively. Thus, it will be seen that the members 14, 18 and the members 15 and 19 may be separated or swung toward each other, the members 18 and 14 pivoting about the hinge pin 21, in such manner that the central portions 12 and 17 may be swung into clamping, or disengaging, relation to a cable, not shown. The 30 central portion 17 of the member 11 is provided with a longitudinally extending semi-cylindrical recess 30 adapted to register with the recess 13 to provide a cylindrical bore.

The member 17 is also provided with a cylindrical bore 31 extending at a right angle to the axis of the recess 30 within which is positioned a cylindrical rotatable bushing member 32, provided with a centrally disposed square aperture 33 into which extends a square shank portion 34 graduated, as at 35. The upper extremity of the member 32 is graduated, as at 36, and an indicating pointer 37 is suitably secured to a mid point of the portion 17. A suitable aperture in the member 32 accommodates a set screw 38 adapted to engage the shank 34, releasably,

in such manner that the shank may be moved vertically upwardly or downwardly within the bore 33.

The member 32 is rotatable within the bore 31, and is provided with a plurality of apertures 40 at spaced intervals about the periphery thereof, adapted to engage spring-pressed headed retaining members 41. As best shown in Figure 3, each of the members 41 is comprised of a pin 42 and a head 43, a compression spring 44 being positioned between the head and the portion 17.

The lower extremity of the shank 34 is bifurcated, as at 45, and carries upon a screw 46 extended through suitable apertures cut in the sides of the bifurcations, a rotatable cutting blade or wheel 47.

Guide members 50 are adapted to be positioned in the semi-cylindrical recess 13, being held in place by set screws 51. Cooperating guide members 52 are correspondingly adapted to be positioned in the recess 30 and held in place, as by screws 53, the heads of the screws 53 and 51 being suitably countersunk to be flush with the walls of the guide. The guide members are semi-cylindrical to form a substantially cylindrical recess of a size adapted to slidably encompass a cable to be stripped. The guide member 52 is provided with a centrally positioned opening 54, through which the cutter blade 47 is adapted to extend, the dimensions of the opening being such that the member 34 may pass therethrough if necessary to accommodate a given depth of cut.

The guide members 50 and 52 are, as will be seen, replaceable by others of different thickness to accommodate a variety of sizes of cables and form inserts.

In the modification shown in Figure 8, an insert 60 is substituted for the guide member 50, being provided with a V-shaped depression 61 extending longitudinally thereof, and being held in position, as by countersunk screws 62. When this form of insert is utilized, the insert 52 may be omitted as desired.

The guide members 50 and 52, in varying dimensions, are adapted to be utilized for cables of varying relatively small size, while the insert of the type shown at 60 may be advantageously utilized with large cables.

From the foregoing, the method of operation of the device should now be readily understandable.

When it is desired to strip a particular cable or section of cable, guide members 50, 52, or inserts, as at 60, of a desired size and configuration, according to the diameter of the cable, not shown, to be stripped are provided and secured in the recesses 13 and, if necessary, 30. The cutter 47 is then aligned, either longitudinally with respect to the cable, or set at a desired angle thereto to provide a helical cut, by pulling out the pins 42 and rotating the bushing member 32 to dispose the cutter blade 47 at a desired angle with respect to the longitudinal axis of the portion of a cable passing through the guide members 50, 52, or, through the recess 30 and the insert 60, as the case may be. The cutter blade 47 is then adjusted to cut through the sheathing of the cable, to a desired depth, by adjusting the shank 34 in the bushing member 32 and setting said

shank at the desired adjustment by means of the set-screw 38.

With the central portions 12, 17 swung into the described clamping relation to a cable, and the members 14, 18 and 15, 19 swung toward each other into engagement, the guide members 50, 52, or the insert 60 and the recess 30, if the insert 60 is used, confine the cable therein for sliding movement in the same. Now, by using the members 14, 18 and 15, 19 as pairs of handle bars, the portions 12, 17 may be pulled along the cable without turning the same to slit the sheathing of the cable in a straight line, if the cutter blade 47 has been aligned with the portion of the cable along which the portions 12, 17 are pulled. If the cutter blade 47 has been set at an angle, as described, the members 14, 18 and 15, 19 may be used in pulling to rotate the portions 12, 17 about the cable so that said blade 47 will cut, or slit, in a spiral path.

From the foregoing, it will now be seen that there is herein provided a device accomplishing all the objects of this invention and others, including advantages of great practical utility and commercial importance.

Modifications of the invention, as described, may be resorted to within the scope of the appended claim.

I claim:

30 In a cable stripper, in combination, an upper portion having a semi-cylindrical recess therein, a lower portion having a semi-cylindrical recess therein in aligned relation with said first-mentioned recess to form a cylindrical bore, a cutter blade extending into the recess of the upper portion, and handle members extending from opposite sides of each of said portions in pairs, one pair being pivotally connected, and means to mount the cutter blade in said upper portion comprising a bushing member rotatably adjustable in said upper portion about an axis at a right angle to the axis of said bore, snap-action devices in said upper portion and bushing member for releasably locking the bushing member in different adjusted positions, and a square shank carrying said cutter blade and slidably mounted in said bushing member for longitudinal adjustment in said bushing member in the axis thereof into different positions, and manipulative means for locking said shank in said different adjusted positions.

CHARLES S. VAUGHAN, JR.
